CLAIM

The ornamental design for a clip lock fastener, as shown and described.

DESCRIPTION

FIG. 1 is perspective view of a clip lock fastener embodying our new design;

FIG. 2 is a front elevational view thereof; the rear elevational view being a mirror image thereof;

FIG. 3 is a sectional view take along line 3-3 in FIG. 2;

FIG. 4 is a right side elevational view thereof; the left side elevational view being a mirror image thereof;

FIG. 5 is a top plan view thereof; and,

FIG. 6 is a bottom plan view thereof.
